(57) **CLAIM**

The ornamental design for a medical imaging device as shown and described.

DESCRIPTION

FIG. 1 is a front view of a medical imaging device and control component thereof showing our new design;

FIG. 2 is a back elevational view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a top, front, right-side perspective view thereof; and,

FIG. 8 is a top, back, left-side perspective view thereof.

The broken lines in the drawings represent portions of the medical imaging device that form no part of the claimed design.

1 Claim, 8 Drawing Sheets
